UNITED STATES PATENT OFFICE.

WALLACE C. CLARK, OF NEW YORK, N. Y.

DESIGN FOR A CASING FOR INHALATION APPARATUS.

SPECIFICATION forming part of Design No. 32,479, dated April 10, 1900.

Application filed February 24, 1900. Serial No. 6,422. Term of patent 7 years.

To all whom it may concern:

Be it known that I, WALLACE C. CLARK, a citizen of the United States, residing at New York, in the county of New York and State of New York, have invented and produced a new and original Design for a Casing for Inhalation Apparatus, of which the following is a specification, reference being had to the accompanying drawings, forming part thereof.

Figure 1 is a side elevation. Fig. 2 is an end view.

As shown in the drawings, the leading or material feature of my design relates to the arrangement of the casing for use in a physician's parlor, whereby it shall present a finished appearance to the patients to be treated; and it consists in a plurality of elongated cylinders 1. The cylinders 1 are disposed one above the other in vertical alinement and supported by means of cylindrical bases 2, also arranged in vertical alinement with the cylinders, from which project vertical standards 3 of smaller diameter than that of the bases, the standards and cylinders being connected

by the reduced cylindrical supports 4, which are connected with the cylinders and standard, respectively. To lend a finished appearance, the upper ends of the bases 2 and also the front ends of the cylinders 1, in which the supports 4 enter, are rounded, as at 5 and 6, respectively, whereby the standards 3 project from the center or greatest convexity of the bases, as do the supports 4 from the cylinders, thereby presenting a finished appearance when viewed either in perspective or end elevation.

Having described my invention, what I claim as new, and desire to secure by Letters Patent, is—

The design for a casing for inhalation apparatus as herein shown and described.

In testimony whereof I have signed my name to this specification in the presence of two subscribing witnesses.

WALLACE C. CLARK.
